UNITED STATES PATENT OFFICE.

EDWIN JAMES COOPER, OF WIMBLEDON, ENGLAND.

NEWSPAPER-PAGE.

SPECIFICATION forming part of Letters Patent No. 740,242, dated September 29, 1903.

Application filed July 9, 1900. Serial No. 23,066. (No model.)

To all whom it may concern:

Be it known that I, EDWIN JAMES COOPER, a British subject, residing at No. 11 Rosslyn Villas, Delamere road, Wimbledon, in the county of Surrey, England, have invented a new and useful Newspaper-Page, of which the following is a specification.

My invention relates to the pages of newspapers of too great a size to be perused conveniently without being first by the reader longitudinally and transversely folded or doubled back flat. Now in so folding or doubling the page of a newspaper back preparatory to perusing it (or rather half of it) the reader necessarily has of course to make the folds down and across certain parts of the reading matter, and having read that half of the page in order to peruse the parts down which the longitudinal fold was made (as well as to peruse the rest of that half of the page) he has to unfold the page and down and across matter that he has perused already to refold it. In this way the folding, unfolding, and refolding demanded of the reader becomes in the case of a newspaper possessing an average number of pages very considerable, wasting time, and, moreover, being vexatious and fatiguing. Where of course the reader instead of first folding the page back longitudinally and then transversely adopts the opposite course—that of folding the page first transversely and then longitudinally—the expenditure of time and trouble is greater still.

Now the object of my invention is to reduce the folding, unfolding, and refolding I have described to a minimum in order that the printed matter on the page may be perused with greater facility and in greater comfort. This desirable result I effect in a special, novel, and simple manner, which will be understood from an examination of the accompanying drawing and from a perusal of the following description:

The drawing represents, made up on the principle of my invention, a single large page of a newspaper. The outermost line A represents the edges of the paper on which the page of matter is printed. The spaces marked B and those similar to them bounded by dotted lines indicate half-columns of reading matter. The small dotted square C rep-

resents the "folio" or number of the page. The horizontal dotted space D shows the position of the "running head"—i. e., the title, date, and the like. The lines marked E and similar ones indicate lines separating the columns of matter from each other.

F represents a line along the page between the running head and the top of the columns of matter.

Now it will be seen that the newspaper-page invented by me has a space G G running downward longitudinally and one H H running crosswise transversely. These spaces I call "folding-spaces," and it is by means of them that I achieve the object of my invention, for, as will be readily understood, if a page of reading-matter so arranged be first folded back flat along the longitudinal folding-space and then folded back flat along the transverse folding-space, or, rather, along one half of it, all the contents of the page on one side of the longitudinal folding-space—namely, whichever side be outermost—may be perused without the reader having to unfold and refold the page further. In order for the other half of the contents of the page—namely, the matter on the other side of the longitudinal folding-space—to be perused, all that is required is for the page to be first unfolded transversely, then turned over, and then folded back transversely in the opposite direction to that in which it was transversely folded before. The minimum width of a folding-space I make just sufficient when the entire bulk of the newspaper has, as above described, been folded for reading to permit of the matter nearest the folding-space being perused easily on the newspaper being held by hand or otherwise in a stationary manner straight in front of the reader.

As will be understood, the purpose of my invention—namely, the facilitating of the reading of large newspaper-pages by the minimizing of the necessary folding—may, albeit not so well, be achieved by the employment of only the longitudinal folding-space and not of the transverse one as well—that is to say, if a page in which there is a longitudinal folding-space be first folded back flat along that space and then folded back flat in half transversely it is possible for the reading matter to be perused almost

as easily as though where the transverse fold is made there were a folding-space. Hence I do not invariably employ the transverse folding-space, the only folding-space absolutely essential being the longitudinal one.

15 I am aware that reading matter is frequently issued to the public printed on a large sheet of paper folded into separate small pages, into which small pages the matter is divided up, and I do not claim for this principle.

What, however, I do claim, and desire to secure by Letters Patent, is—

15 1. A printed page having its columns of letterpress arranged in one direction—namely, to read from top to bottom—as in the case of an ordinary newspaper; said page being too large to be perused conveniently, while being held in the hand, without its being doubled 20 back flat first longitudinally and then transversely, or vice versa, to a quarter of its size; and its columns of letterpress being divided into two groups by a longitudinal “folding-space” located in the center of the page and 25 sufficiently wide to allow the page to be doubled back flat, substantially as described.

2. A printed page constituting one of a number contained in the same publication and having its columns of letterpress arranged in one direction—namely, to read from top to bottom—as in the case of an ordinary newspaper; said page being too large 30 to be perused conveniently, while being held in the hand, without its being doubled back flat first longitudinally and then transversely, or vice versa, to a quarter of its size; and its columns of letterpress being divided into two groups by a longitudinal “folding-space” located in the center of the page and sufficiently 35 wide to allow the entire bulk of the publication to be doubled back flat, substantially as described.

40 tion to be doubled back flat, substantially as described.

3. A printed page having its columns of letterpress arranged in one direction—namely, to read from top to bottom—as in the case of 45 an ordinary newspaper; said page being too large to be perused conveniently, while being held in the hand, without its being doubled back flat first longitudinally and then transversely, or vice versa, to a quarter of 50 its size; and its columns of letterpress being divided into two groups by a longitudinal “folding-space” located near the center of the page and sufficiently wide to allow the page to be doubled back flat, substantially as 55 described.

4. A printed page constituting one of a number contained in the same publication and having its columns of letterpress arranged in one direction—namely, to read from 60 top to bottom—as in the case of an ordinary newspaper; said page being too large to be perused conveniently, while being held in the hand, without its being doubled back flat first longitudinally and then transversely, or 65 vice versa, to a quarter of its size; and its columns of letterpress being divided into two groups by a longitudinal “folding-space” located near the center of the page and sufficiently wide to allow the entire bulk of the 70 publication to be doubled back flat, substantially as described.

In testimony whereof I have signed my name to this specification in the presence of two subscribing witnesses.

EDWIN JAMES COOPER.
